US00D402381S

United States Patent [19]

Gruda et al.

[11] Patent Number: Des. 402,381

[45] Date of Patent: **Dec. 8, 1998

[54] INJECTION MOLDED LATTICE

[75] Inventors: **James B. Gruda**, Rochester; **William D. Goslin**, Whitmore Lake; **Carl I. Schwartz**, Grand Blanc; **Richard W. Cantley**, Troy, all of Mich.

[73] Assignee: **PRC Corporation**, Flint, Mich.

[**] Term: **14 Years**

[21] Appl. No.: **23,895**

[22] Filed: **Jun. 2, 1994**

Related U.S. Application Data

[63] Continuation of Ser. No. 1,884, Nov. 23, 1992, abandoned.

[57] CLAIM

The ornamental design for an injection molded lattice, as shown and described.

DESCRIPTION

FIG. 1 is a fragmentary perspective view of the design for a molded plastic lattice of the present invention, the pattern is repetitive as shown in FIG. 1 of the drawing;

FIG. 2 is an enlarged fragmentary view of a portion of the design for molded plastic lattice of FIG. 1;

FIG. 3 is a transverse cross-sectional view taken substantially along the line 33 of FIG. 2;

FIG. 4 is a transverse cross-sectional view taken substantially along the line 44 of FIG. 2; and,

FIG. 5 is a side elevational view of the back side of the lattice design shown in FIG. 2.

The design is characterized by the specific combination of features comprised of a first set of diagonal slats unitarily formed with a second set of oppositely running diagonal slats to form a lattice with a height offset between the first set of diagonal slats and the second set of diagonal slats to provide a unitarily formed lattice having the second set of diagonal slats positioned on top of the first set of diagonal slats, all as best illustrated in FIGS. 1, 2, 3, 4 and 5.
